UNITED STATES PATENT OFFICE.

HERBERT G. THOMAS, OF LAKE FOREST, ILLINOIS.

VALVE FOR HOT-WATER HEATING SYSTEMS.

No. 917,813.

Specification of Letters Patent.

Patented April 13, 1909.

Application filed November 11, 1907. Serial No. 401,624.

To all whom it may concern:

Be it known that I, HERBERT G. THOMAS, a citizen of the United States, residing at Lake Forest, in the county of Lake and State 5 of Illinois, have invented a certain new and useful Improvement in Valves for Hot-Water Heating Systems, (Case 1,) of which the following is a full, clear, concise, and exact description, reference being had to the 10 accompanying drawings, forming a part of this specification.

My invention relates to hot water heating systems, and has for its object to improve the apparatus used whereby the efficiency of 15 such systems may be increased.

In the past a great part of the energy contained in the heated water used in such systems as a means for conveying heat from the fire to the place to be heated has been lost on 20 account of the apparatus used not properly facilitating the flow of water. In many cases there is serious interference between the currents of water entering and leaving the radiator, and the result is a serious loss of 25 efficiency in heating.

It is the object of my invention to overcome these objections by providing means for preventing interference between the water currents in such systems, and I have 30 shown my invention embodied in a valve mechanism adapted to be connected to a radiator and adapted to control the flow of water into and away from such radiator, and also to direct the water both on entering and 35 leaving the radiator so it will flow to its proper passageway without hindrance.

A further object of my invention is to construct a valve for accomplishing the above indicated results that will be compact in 40 every way, to facilitate decreasing the distance between the radiators and the floor and to decrease the distance between the supply and return pipes.

The several drawings illustrating my invention are as follows:

Figures 1, 2 and 3 are end, side and top views of my improved valve assembled; Fig. 4 is a transverse sectional view taken along the dotted line $x-y$ in Fig. 2; Fig. 5 is a 50 longitudinal sectional view taken along the dotted line x^2-y^2 in Fig. 3; Fig. 6 is a longitudinal sectional view taken along the dotted line x^1-y^1 , Fig. 2.

Similar letters refer to similar parts 55 throughout the several views.

Referring to the figures, the valve consists

essentially of a body portion v formed integrally with which are supply and return connections adapted to be connected to suitable pipes by the unions u , u^1 . Connection is 60 made with the radiator by a removable section v^6 connected to the valve portion by a union u^2 . The section v^6 is made removable in order to facilitate securing such section to the radiator, and after this is in place the 65 valve proper is secured thereto by means of the union mentioned. The main body part of the valve is provided with a horizontal partition v^7 extending throughout its length excepting where cut away to permit the 70 operation of the gate v^4 . This horizontal partition v^7 is continued in the section v^6 by the horizontal partition v^3 , which terminates at its outer end in an up-turned portion, or lip. The gate v^4 is connected to a stem v^8 75 extending through the closing plug v^1 of the valve and is adapted to be moved from one position to another by the operating handle h . Leakage is prevented around the stem v^8 by a suitable stuffing box v^2 , as indicated. 80

The gate v^4 is adapted to be moved from the position indicated in Fig. 4, which is the open position, to a horizontal position which is the closed position, and a partition v^5 extending from the horizontal partition v^7 to 85 the outside shell of the valve is provided to form a continuous opening from the inlet pipe to that part of the inside of the valve above the partition v^7 and v^3 . The portion of the body part of the valve below the horizontal 90 partition v^7 and v^3 forms a continuous passageway to the outlet pipe secured to the valve by the union u^1 . The gate v^4 is adapted to fit closely between the partition v^5 and the closing plug v^1 to prevent leakage around 95 such gate directly from the inlet opening to the outlet opening when the gate is in the position indicated in Fig. 4. When the gate is moved to the position indicated in dotted lines in Fig. 4, it serves to entirely cut off the 100 communication between the inlet opening and that part of the valve above the horizontal partition, and at the same time to form a continuous passageway from the inlet opening directly to the outlet opening. 105

It is to be observed that the up-turned end of the partition v^3 serves not only to direct the water entering the radiator, but also to direct the water returning from the radiator to the passageway below the horizontal partitions, and thus constitutes a means for preventing interference between the water 110

currents entering and leaving the radiator. When the gate v^4 occupies its closed position, the water will circulate directly from the supply pipe connection to the outlet pipe connection. This is of great advantage, inasmuch as the hot water is always available at the radiator and no time is required to start the flow through the supply and return pipes and also this serves as a protection to such pipes in exposed positions in cold weather.

While I have shown my invention in the embodiment above described, I do not limit myself to the particular detail herein shown, but claim broadly any modifications for accomplishing the results hereby secured that will suggest themselves to those skilled in the art.

What I claim is:

1. In a valve for a hot water radiator, a body portion having supply and return passages, supply and return connections, and a single valve closure adapted to connect such supply and return passages with the supply and return connections respectively when such valve closure is in one extreme position, and adapted to connect such supply and return connections together directly when such valve closure is in the other extreme position, intermediate positions of the valve closure serving to permit water flowing into the supply connection to divide, a part going into the return connection directly and part to the radiator and thence to the return connection without interference between the two water currents thus produced.

2. In a valve for a hot water radiator, a body portion having supply and return passages, supply and return connections, and a single valve closure adapted to connect such supply and return passages with the supply and return connections respectively when such valve closure is in one extreme position and adapted to connect such supply and return connections together directly and interrupt connection between the supply connection and supply passage when such valve closure is in the other extreme position, intermediate positions of the valve closure serving to permit water flowing into the supply connection to divide, a part going into the return connection directly and part to the radiator and thence to the return connection without interference between the two water currents thus produced.

3. In a valve for a hot water radiator, a body portion having horizontal supply and return passages, a single connection between the valve and the radiator, supply and return connections, and a single valve closure adapted when in one extreme position to prevent communication in the valve between the supply and return connections and when in the other extreme position to prevent communication between the supply connec-

tion and the supply passage, the last mentioned position serving also to establish communication between the supply and return connections.

4. In a valve for a hot water radiator, a body portion having supply and return passages, supply and return connections, and a single valve closure adapted when in one extreme position to prevent communication in the valve between the supply and return connections and when in the other extreme position to prevent communication between the supply connection and the supply passage, the last mentioned position serving also to establish communication between the supply and return connections.

5. In a valve for a hot water radiator, a body portion, a horizontal partition dividing the body portion into supply and return passages, such partition extending beyond the body portion through a single connection to the radiator, such partition adapted when the valve is in place to direct the water both on entering and leaving the radiator, supply and return connections and a flat gate adapted to connect such supply and return passages with the supply and return connections respectively when the gate is in one extreme position and adapted to connect such supply and return connections together directly when the gate is in the other extreme position, intermediate positions of the gate serving to permit water flowing into the supply connection to divide and part go to the return connection directly and part to the radiator and thence to the return connection without interference between the two water currents thus produced.

6. In a valve for a hot water radiator, a cylindrical body portion, a horizontal partition dividing the body portion into semi-cylindrical supply and return passages, such partition extending beyond the body portion and adapted when the valve is in place to direct the water both on entering and leaving the radiator, supply and return connections and a flat gate adapted to connect such supply and return passages with the supply and return connections respectively when the gate is moved to a nearly vertical position and adapted to connect such supply and return connections together directly when the gate is practically horizontal.

7. In a valve for a hot water radiator, a body portion, a horizontal partition dividing the body portion into supply and return passages, such partition extending beyond the body portion and adapted when the valve is in place to direct the water both on entering and leaving the radiator, supply and return connections and a flat gate adapted to connect such supply and return passages with the supply and return connections respectively when the gate is moved to a nearly vertical position and adapted to connect such

supply and return connections together directly when the gate is practically horizontal, intermediate positions of the gate serving to permit water flowing into the supply connection to divide and part go to the return connection directly and part to the radiator and thence to the return connection without interference between the two water currents thus produced.

8. In a valve for a hot water radiator, a cylindrical body portion, a common connection between the valve and the radiator, such connection constituting a continuation of the cylindrical body portion, a horizontal partition dividing the body portion into semi-cylindrical supply and return passages, such partition extending through such connection beyond the valve and adapted when the valve is in place to direct the water both on entering and leaving the radiator, supply and return connections and a single flat gate adapted to connect such supply and return passages with the supply and return connections respectively when the gate is moved to one position and adapted to connect such supply and return connections together directly when the gate is moved to another position, intermediate positions of the gate serving to permit water flowing into the supply connection to divide and part go to the return connection directly and part to

the radiator and thence to the return connection without interference between the two water currents thus produced.

9. In a radiator valve, a valve body provided with a supply passage and a return passage, both of said passages being adapted to communicate with a radiator at one end and at the other end with supply and return connections respectively, said body being also provided with a passage connecting said supply and return passages, a single valve closure adapted to close the supply passage to the radiator when in one position and to close said connecting passage when in another position, said valve closure being capable of taking any intermediate position, thereby restricting more or less said connecting passage, whereby the flow through the supply passage to the radiator may be increased, the flow through the connecting passage being correspondingly decreased, or the flow through the supply passage may be decreased and the flow through the connecting passage correspondingly increased.

In witness whereof, I hereunto subscribe my name this 7th day of November A. D., 1907.

HERBERT G. THOMAS.
